UNITED STATES PATENT OFFICE.

JOHN S. THOMPSON, OF CHICAGO, ILLINOIS.

SLUG-CASTING MACHINE.

1,290,805.

Specification of Letters Patent. Patented Jan. 7, 1913.

Application filed April 28, 1917. Serial No. 164,017.

To all whom it may concern:

Be it known that I, JOHN S. THOMPSON, a citizen of the United States, residing at Chicago, in the county of Cook and State of Illinois, have invented new and useful Improvements in Slug-Casting Machines, of which the following is a full, clear, concise, and exact description, reference being had to the accompanying drawing, forming a part 10 of this specification.

My invention relates to improvements in slug casting machines, and particularly to improvements in machines for casting a line of type wherein the face of the type is of 15 large dimensions, particularly adapted for display printing, and the like.

One of the objects of my invention is to provide a mold for casting such type whereby the ordinary matrices of the linotype machine may be used for forming the front 20 face of the type, it being understood that in the preferred embodiment of my invention the printing unit comprises a complete line, just as does the linotype slug comprise a 25 complete line in itself.

For the purpose of disclosing my invention I have illustrated in the accompanying drawings one embodiment thereof.

In said drawings—

Figure 1 is a side elevation of a machine embodying my invention;

Fig. 2 is a plan view thereof;

Fig. 3 is a sectional view taken on the line 3—3 of Fig. 2;

Fig. 4 is a front elevation of the head mold;

Fig. 5 is a perspective view of the mold box showing one of the linotype matrices placed in position;

Fig. 6 is a perspective view of a linotype matrix;

Fig. 7 is a perspective view of one of the side members of the mold box; and

Figs. 8, 9 and 10 are side elevations of a 45 slug cast by my machine.

In the embodiment illustrated in the accompanying drawings, I provide a suitable supporting frame 1, on which is movably mounted a metal pot 2 of the usual type used 50 in linotype machines. This pot 2 is hingedly supported at 3 by means of a hingedly mounted supporting frame 4 and is adapted to be moved back and forth or toward and away from the mold during the casting operation. The pot is provided with the usual 55 metal delivery nozzle 5, which fits up tightly,

when the pot is moved forward, against the base casting mold 6. This base casting mold is vertically movable with respect to the pot and is supported on a suitable frame 7. The frame is vertically movable on a pair of guide rods 8, which at their lower ends are hingedly mounted on the frame 1, and is provided with adjustable up and down stops 9 and 10, which limit the upward and downward movement of the frame and base casting mold. For the purpose of raising and lowering the frame and with it the base casting mold, I provide a rocking arm 11 having at its outer end a pivoted block 12, through which projects a connecting rod 13 pivotally connected at 14 with the base casting mold frame. The rod 13 is provided with a pair of adjustable nuts 15 and 16, which act as abutments for the coiled springs 17 and 18 interposed between them and the block 12 to form cushions for this block and to take up the lost motion of the arm 11. The arm is rigidly connected to a shaft 19, which is provided with a crank arm 20 connected with an arm 21, which at its outer end is provided with a roller 22 operating in a cam slot 23 on a suitable drive wheel. It is obvious that as the wheel is rotated the roller operating in the cam slot 23 will cause the arm 21 to move up and down, thereby rocking the crank 20 and, in turn, rocking the arm 11 to raise and lower the base casting mold at regular timed intervals.

The base casting mold, when in its raised 90 position, is interposed between the nozzle 5 of the melting pot and a head casting mold body 24, which mold is stationarily mounted on a head 25, which head is secured on a pair of projecting arms 26 of the frame 1.

The head casting mold body comprises the rear block 27, the bottom block 28, which is preferably integral with the rear block, the two side blocks 29 and 30, and the top block 31. The rear and bottom blocks are made in one piece and the bottom block rests upon a pair of adjustable screw rests 32 secured in lugs 33 extending from the head 25. The rear block is provided with a projection 34, which fits in a suitable vertical groove 35 formed in the front face of the head 25 to prevent lateral displacement thereof. Each of the side blocks is provided with a longitudinal groove 36, which slips over a tongue 37 on the two side members 38 projecting forwardly from the head 25 and which serve to retain the blocks in position.

on the head. The top member 31 is provided with a pair of dowel openings 38 which slip over the dowel pins 39 on the rear member 27 to prevent lateral displacement 5 of this top member. There is thus constructed an open front mold box which is supported upon the stationary head 25. The linotype matrices are arranged within this box as indicated. The inside face of the 10 rear member 27 of the box is provided with a tongue 27^a which fits within the rear recess of the matrix, in order that a firm support may be given thereto. The matrices are arranged within this box side by side to form 15 the proper mold face, and within the box on each side of the line of matrices is inserted a plate 40 having guiding notches 41 and 42. The end piece 30 is provided with a thumb-screw 43 by which the entire line 20 of matrices is clamped securely in place, and the top 31 is provided with a downwardly extending flange 44, which fits over the outer edge of the matrices to prevent any tendency on their part to pull out of the 25 mold box. Arranged along the front face of the mold box and fitting in the guiding notches 41 and 42 of the side plates 40 are a pair of strips 45 which form the top and bottom of the head mold, the matrices, of 30 course, forming the front of the mold and the projecting portions 46 of the side plates 40 forming the sides of the mold. The strips or rails at their ends drop into longitudinally extending slots in side members 47, 35 which are bolted to the head and are thus held in place.

The operation of molding the slug is as follows: Assuming the parts to be in the position shown in Fig. 1, when the metal pot 2 40 is forced forward the nozzle 5 is forced into engagement with the rear face of the base casting mold 6 and the front face of this mold is forced into engagement with the front face of the head casting mold, the 45 surface of the mold 6 abutting against the rails 45 and the side portions 46, thereby completely inclosing the sides and top and bottom of the head casting mold. The movement of the member 6 is permissible 50 due to the fact that the frame carrying the base casting mold is mounted on the pivoted rods 8. As soon as the parts are thus all forced into compact engagement the metal is forced by the usual pump out of the metal 55 pot through the nozzle into the base casting mold and into the head casting mold, where it immediately sets and a slug is formed having a base 47' and a head 48, the front face of the head having formed thereon the 60 suitable printing indicia 49. As soon as the cast is made the metal pot is released and moves backward and the base casting mold 6 is moved away from the head casting mold under the influence of a plunger 50 operated 65 by a coiled spring 51 mounted on the station-

ary frame 1. This plunger bears against a cross piece 52 of the frame of the base casting mold and has a constant tendency to force the same away from the head casting mold. As soon as the base casting mold has 70 moved away from the head casting mold, carrying with it the base and the cast head, it is moved downwardly, and in so doing the rear face slides across a stationarily mounted knife edge 53, whereby the base is trimmed 75 and continues in its movement until the opening of the base casting mold is directly opposite the ejector 54. This ejector is horizontally movable and is supported on the frame 1, being operated by means of a pair 80 of reciprocating arms 55, which are moved forwardly by the crank 56 operated by the cam 57 on the driving shaft. The ejector 54 is retracted by means of a coiled spring 58 interposed between a stop 59 on the frame 85 and a stop or abutment 60 on the rod 55. The ejector moving forward presses against the base of the cast and forces the same outwardly, so that it drops out of the base casting mold and into the receiving pan 61 on 90 the frame, after which the ejector 54 is retracted out of the path of the base casting mold and the base casting mold is again raised in position to repeat the above described operation. 95

In order that when the ejector operates to push the slug out of the base casting mold the mold will not move, I provide a pair of stationary adjustable buttons 62 for the mold frame when it reaches its lower position, to hold the same against horizontal movement. 100

In Figs. 8, 9 and 10 I have illustrated three forms of cast slugs. It will be noted that the only difference in these forms is 105 the relative location of the base with respect to the head. This is accomplished by adjusting the supporting screws 32 so that the relative position of the head mold body is vertically changed, whereby the position of 110 the head mold with respect to the base mold is changed to vary the relative location of the base on the head.

Having thus described my invention, what I claim as new and desire to secure by Letters Patent, is:—

1. In a type casting machine, the combination with a base casting mold, of a head casting mold comprising four separate walls and a face matrix. 120

2. In a type casting machine, the combination with a base casting mold, of a head casting mold comprising a four-walled mold and a matrix forming the face of the head casting mold. 125

3. In a type casting machine, the combination with a base casting mold, of a head casting mold comprising a four-walled mold and a plurality of matrices forming the face of said head casting mold. 130

4. In a type casting machine, the combination with a base casting mold, of a head casting mold comprising a removable frame forming a mold cavity and a plurality of standard linotype matrices forming the face of said mold cavity.
5. In a type casting machine, the combination with a head casting mold comprising a face member and a frame forming a mold cavity, of a base casting mold narrower in width than said head casting mold and movable in close proximity thereto, and a metal melting pot having a nozzle movable into injecting position on said base casting mold.
- 10 6. In a type casting machine, the combination with a head casting mold comprising a face mold and a frame forming a mold cavity, of a base casting mold forming with said head casting mold a complete slug mold and reciprocally mounted with respect to said head casting mold, and a horizontally movable ejector coöperating with said base casting mold to eject the slug therefrom when the base casting mold, and with it the casting, are moved away from the head casting mold.
- 15 7. In a type casting machine, the combination with a base casting mold, of a head casting mold comprising a mold body, a plurality of matrices arranged in said mold body to form the front face of the casting mold, a pair of mold sides and a pair of removable rails removably secured against the front face of said matrices to form the top and bottom of the head casting mold.
- 20 8. In a type casting machine, the combination with a base casting mold, of a head casting mold comprising an open-faced box forming a mold body for the reception of a plurality of linotype matrices, a pair of side members mounted in said box forming the side members of the mold, and a pair of removable strips arranged on the face of said matrices between the ears thereof to form the top and bottom of the head casting 40
- 25 45
9. In a type casting machine, the combination with a base casting mold, of a stationary supporting head, a head casting mold removably mounted thereon and comprising an open-sided box, a plurality of matrices mounted in said box and forming the face of said head casting mold, a pair of mold sides and a pair of removable strips placed across the front face of said matrices to form the top and bottom of said head casting mold.
- 30 50
10. In a type casting machine, the combination with a head casting mold, comprising a mold cavity frame and a plurality of matrices, of a base casting mold coöperating with said head casting mold to form a single slug mold, a horizontally movable melting pot having a nozzle movable into injecting 60
- 35 65
- position with respect to the base casting mold, said base casting mold being horizontally and vertically movable.

In witness whereof I have hereunto subscribed my name.

JOHN S. THOMPSON.
